UNITED STATES PATENT OFFICE.

JAMES N. EUWER, OF NEW YORK, N. Y.

SPRING-TIRE.

1,147,154.

Specification of Letters Patent.

Patented July 20, 1915.

Application filed August 10, 1914. Serial No. 855,990.

To all whom it may concern:

Be it known that I, JAMES N. EUWER, a citizen of the United States, residing in the city of New York, borough of Manhattan, in 5 the county and State of New York, have invented a certain new and useful Improvement in Spring-Tires, of which the following is a specification.

The invention relates to resilient wheels 10 for automobiles and analogous vehicles, and the object of the invention is to provide simple, efficient and economical means whereby the desired resiliency is obtained by metallic springs located in the rim of the 15 wheel, thus avoiding various objectionable characteristics inherent in the pneumatic tire.

The invention consists in certain novel features of construction and arrangement 20 by which the above objects are attained, to be hereinafter described and claimed.

The accompanying drawings form a part of this specification and show an approved form of the invention.

25 Figure 1 is a side elevation of a portion of a wheel constructed in accordance with the invention, certain parts being removed, and partly in vertical section. The succeeding figures are on a larger scale. Fig. 2 is 30 a vertical section corresponding to a portion of Fig. 1, and partly in side view. Fig. 3 is a transverse section taken on the line 3—3 in Fig. 2. Fig. 4 is a side elevation of one of the radially movable members or sections. Fig. 5 is a corresponding side view. Fig. 6 is a horizontal section through one 35 of such members and a portion of the rim, and partly in plan view, the plane of section being indicated by the line 6—6 in 40 Fig. 5.

Similar letters of reference indicate the same parts in all the figures.

The device comprises a series of radially movable sections or members of peculiar 45 construction mounted and guided in the wheel-rim and forced yieldingly outward by leaf springs arranged annularly on the rim and having outwardly curved portions coacting with such members.

50 A is the wheel-rim of channel form having continuous peripheral flanges A¹ A¹ carrying on the inner face of each a series of bosses or lugs A² A².

55 B B are the movable members stamped by suitable dies to the U-form shown, having the end portions or legs B¹ B¹ adapted to fit

within the rim-flanges and slotted as at b to receive the lugs A² by which the sections are guided in their radial movements and such movements limited. Each member or 60 section B is arched transversely of the rim and is provided with an outwardly projecting convex ridge B² which receives the impact with the roadbed, and the sections are each reinforced by a brace or stiffening plate 65 B³ secured to the leg portions B¹ B¹ and extending into the interior of the convex ridge B². The brace is held by riveting the wings B⁴ B⁴ thereon to the leg portions, and the brace is continued as ears B⁵ B⁵ serving as 70 supports or bearings for a transverse anti-friction roller C mounted in such ears with liberty to revolve. The slots b are formed by slitting the metal of the leg portion B¹ and bending inwardly the flanges thus produced, as at B⁶ B⁶.

On the outer circumferential face of the rim A between the flanges A¹ A¹ are mounted a series of annular springs D extending circumferentially side by side and which 80 may be understood to be each joined at the ends to form a continuous ring, or simply lapped at such ends without fastening. Each spring is of steel, preferably composed of a plurality of leaves or layers, and is of 85 serpentine form in edge view having a series of waves or outwardly curved portions D¹ alternated with the inwardly curved portions in contact with the rim. The springs are loosely secured to the rim by any suitable 90 means, shown as staples E inclosing the springs at the inwardly curved parts and fastened to the rim.

Six springs are shown arranged in pairs, the arches D¹ of the central pair coinciding 95 and the arches of the intermediate pair in coincidence, and the arches of the outer pair similarly located, with the arches of each pair in advance of the preceding a distance equal to the distance between the centers of 100 adjacent rollers C C. The latter are of sufficient length to contact with the arches of any one of said pairs of springs, thus permitting the sections to be uniform and be located in any portion of the rim without 105 special selection. This arrangement of the springs permits the outward curves or arches D¹ to be comparatively long and thus affords a degree of resiliency not easily attained by shorter arches.

110 The compression of the arches at the point of contact of the sections with the

roadbed, causes the arch to flatten and by the loose connection with the rim the spring is permitted to move longitudinally at that point and by increasing the strain on the 5 adjacent arches distribute the strain among the adjacent sections.

In order to present an appearance somewhat similar to the pneumatic tire it is intended to replace, the sections B B with the 10 flanges A¹ A¹ of the rim are inclosed in a casing or shoe F which may be of rubber and fabric, leather, or other suitable material, extending under the margins of the rim A at each side and secured to the inner face 15 thereof, and at each side of the rim are annular cheek-pieces G of wood or other material applied on the outer faces of the flanges A¹ A¹ and rounded to aid in imitating the appearance of the usual air-filled 20 tire.

The convex ridge on each of the sections B serves an important function in offering a definite projecting contact point for the wheel. Two or more ridges of adjacent sections will always be presented to the roadbed, each backed up by the arches of its pair 25 of springs, and favorably arranged for insuring a relatively considerable radial movement under compression.

30 The rim and sections are preferably of cold rolled steel, and the latter are engaged with the lugs on the former by springing the leg portions inwardly to permit their insertion. After such introduction they are held 35 by the engagement of the lugs in the slots b.

The rollers C permit the slight circumferential movement of the springs D without undue friction.

The shape of the sections B may be varied, 40 and the anti-friction rollers omitted. Any number of springs D D may be employed and the relative lengths of the arched portions thereof may be varied to suit conditions.

45 I claim:

1. In a vehicle wheel of the character set forth, a rim having peripheral flanges, a series of lugs on the inner faces of said flanges, a series of U-shaped sections received 50 between said flanges and having radial slots in the leg portions of such sections receiving said lugs, a transverse brace in each of said sections, a roller mounted in said brace, and a continuous flat spring of annular serpentine form loosely mounted on said rim within said sections with its arches arranged to coact with said rollers and resist yieldingly the 55 inward radial movements of said sections.

2. In a vehicle wheel of the character set 60 forth, a rim having peripheral flanges, a series of lugs on the inner faces of said

flanges, a series of U-shaped sections received between said flanges and having radial slots in the leg portions of such sections receiving 65 said lugs, a roller mounted transversely in said sections, and a continuous flat spring of annular serpentine form loosely mounted on said rim within said sections with its arches arranged to coact with said rollers and resist yieldingly the inward radial move- 70 ments of said sections.

3. In a vehicle wheel of the character set forth, a rim, a series of sections radially guided therein, and a plurality of continuous flat springs of annular serpentine form 75 arranged in pairs and loosely mounted on said rim with the arches of adjacent members of the different pairs alternately engageable with said sections.

4. In a vehicle wheel of the character set 80 forth, a rim having peripheral flanges, a series of lugs on the inner faces of said flanges, a series of sections mounted between said flanges and having radial slots in which said lugs are engaged, and a plurality of 85 continuous flat springs of annular serpentine form arranged in pairs and loosely mounted on said rim with the arches of adjacent members of the different pairs alternating and arranged to resist yieldingly the inward 90 radial movements of said sections.

5. In a vehicle wheel of the character set forth, a rim having peripheral flanges, a series of lugs on the inner faces of said 95 flanges, a series of sections mounted between said flanges and having radial slots in which said lugs are engaged, a plurality of flat springs of annular serpentine form arranged in pairs and loosely mounted on said rim within said sections with the arches of adjacent members of the different pairs alternating 100 and arranged to resist yieldingly the inward radial movements of said sections, and a flexible annular shoe inclosing said sections.

6. In a vehicle wheel of the character set forth, a rim, a series of sections radially guided therein, a plurality of continuous flat springs of annular serpentine form arranged in pairs and loosely mounted on said 110 rim with the arches of adjacent members of the different pairs alternately engageable with said sections, and rollers carried by said sections for engagement by said arches.

In testimony that I claim the invention above set forth I affix my signature, in presence of two witnesses.

JAMES N. EUWER.
